S. L. Lount,
Pump.

No. 92,621.

Patented July 13, 1869.

United States Patent Office.

SAMUEL D. LOUNT, OF RATHBONE, WEST VIRGINIA.

Letters Patent No. 92,621, dated July 13, 1869.

IMPROVEMENT IN PUMPS FOR CONTINUOUS DISCHARGE.

The Schedule referred to in these Letters Patent and making part of the same.

To all whom it may concern:

Be it known that I, SAMUEL D. LOUNT, of Rathbone, in the county of Wirt, and State of West Virginia, have invented a new and improved Pump; and I do hereby declare that the following is a full, clear, and exact description of the construction and operation of the same, reference being had to the accompanying drawings, making a part of this specification, in which—

Figure 1 is a cross-section through line $y y$ of fig. 2.

Figure 2 is a longitudinal section through line $x x$ of fig. 1.

The object of this invention is to cause the pump to throw a full and rapid stream of water continuously, and with uniform velocity.

To this end, it is provided with three plungers, all operating in turn upon the same stream of water, and worked by a cam, crank, or other equivalent device, in such a manner that the water is impelled along at all times by that plunger which is at or near its maximum speed, the others, meanwhile, moving back in turn to take their places for another throw.

In the drawings—

M M is the frame of the pump.

P, the pulley, which applies the power.

S, the driving-shaft.

C, a cam-wheel on shaft S, having an inclined groove, e, around it, as shown in fig. 2.

B B¹ B², three plunger-rods, caused to reciprocate, one after the other, by the movement of cam e, as shaft S is rotated.

A A¹ A², three cylinders, connected by the passages E E'.

F F¹ F², the pump-pistons, attached to the rods B B¹ B², and operating in the cylinders A A¹ A², respectively.

G, the induction-pipe.

H, the eduction-pipe.

a a¹ a², valves opening upward, and a¹ a², valves opening downward, the water, in its passage through the pump, taking the direction indicated by the arrows.

Instead of the cam-track, for the purpose of operating the rods B B¹ B², cranks or other equivalent device, arranged upon one or more shafts, may be employed.

In such case, the cranks should be arranged to follow each other, at intervals of about sixty degrees; while, if the cam-track be employed, the cylinders should all be set in a semicircle, as shown in fig. 1, at intervals of sixty degrees from each other.

The object of this construction is, that the water may always be impelled by that crank, or that part of the cam, which is moving up or down most rapidly at any particular time, while those cranks or portions of the cam-track which are passing the dead-points shall have ceased for the moment to have much, if any effect upon the stream.

For example, the rod of piston F, fig. 2, is at its highest elevation, and passing the upper dead-point. At this moment, the next piston moved by that portion of the cam-track which descends most rapidly, is being swiftly forced downward, with its valves closed, and pushing before it all the water in its cylinder.

The effect of the swifter motion of piston F¹ is to draw open the two valves of piston F, and keep a rapid flow of water following, while, at the same time moving more rapidly than piston F², which is at or near the lower dead-point, it forces the water at o, through the passage E', into cylinder A², and through valves a² a² to the eduction-pipe.

As soon as the piston F¹ approaches its dead-point, one of the others is nearing the point where it moves upward most rapidly.

In every case, the lifting or forcing-power is necessarily applied by the most rapidly-moving piston, and the water driven by this piston faster than the other pistons are moving, opens their valves, and passes along without obstruction from said pistons, although all are virtually operating in the same cylinder or water-passage way.

In fact, three pistons may be arranged in a single cylinder, one over the other, to operate in the same way, in which case the cranks would follow each other at intervals of one hundred and twenty degrees; and, on the other hand, no one of the pistons need have the valves opening downward, provided the passages E E' are arranged to carry the water from the top of one cylinder to the bottom of the next.

I do not desire to claim, broadly, a pump having three cylinders, for I am aware that pumps having even a larger number, have, for a long time, been in use.

In my invention, as before remarked, the three cylinders (and there may be more of them) are but parts of one passage-way for the water, and the three pistons all operate upon the same continuous stream.

What I claim as new, and desire to secure by Letters Patent, is—

1. A pump having but one water-passage, in which are combined three or more pistons, F F¹ F², with valves, when so constructed that the intermediate one operates in a direction opposite to that of the two extreme ones, substantially in the manner and for the purposes specified.

2. The combination and arrangement of the shaft S, cam-wheel C, rods B B¹ B², cylinders A A¹ A², pistons F F¹ F², and valves a a¹ a², when constructed to operate substantially as and for the purposes herein set forth.

SAML. D. LOUNT.
